4 Claims. (Cl. 42—76)

The present invention relates to guns making use of ammunition in the form of cartridges, such cartridges including a cartridge case, which is generally metallic, provided with a primer and containing the propelling charge and a projectile tightly fitted in the neck of said cartridge case, for instance by shrinking.

My invention is more especially but not exclusively concerned with automatic guns and in particular those of the open breech type.

The object of my invention is to provide a system of this kind which is better adapted to meet the requirements of practice than those used up to the present time.

The cartridges with which my invention is concerned include at least two annular bearing areas located one ahead of the other and adapted to cooperate with two abutments carried by the gun barrel respectively and also located at a distance from each other. My invention is characterized in that said bearing areas are shaped and located at a distance from each other such that every cartridge, near the end of the movement of introduction thereof into the cartridge chamber, is first braked by deformation of one of said bearing areas on the corresponding cartridge chamber abutment, then positioned in a very accurate manner by cooperation of the second bearing area against the corresponding abutment of the cartridge chamber.

Preferred embodiments of my invention will be hereinafter described with reference to the accompanying drawings, given merely by way of example and in which:

Fig. 1 is a longitudinal sectional view of the cartridge chamber of an automatic gun, with a cartridge being introduced into said chamber, according to my invention.

Figs. 2 and 3 are diagrammatic sectional views on an enlarged scale corresponding to successive positions of the cartridge in the cartridge chamber.

Fig. 4 is a longitudinal sectional view by a horizontal plane, showing a portion of the breech mechanism of a gun according to my invention.

A cartridge according to the present invention essentially includes a cartridge case 2, generally metallic, provided with a primer in its base and containing the propelling powder charge 3 and a projectile 4 tightly fitted in the neck c of said cartridge case, for instance by shrinking. Such a cartridge is to be introduced and suitably positioned in the cartridge chamber 1 of the gun.

It will be understood that whatever be the firing system (either a mechanical or an electrical one), a good operation of the gun will be obtained only if all of the cartridges successively introduced into the cartridge chamber occupy the same position therein at the time of firing.

In other words it is necessary, in order to obtain a satisfactory firing of the cartridges, to prevent any possibility of the successive cartridges being located in slightly different axial positions.

It has already been proposed to obtain this result by providing the cartridge case with an annular flange intended to come into contact with the rear edge of the

2

gun barrel, so as to stop the cartridge when it is introduced into the cartridge chamber and to position it with respect to said chamber.

However, with such an arrangement, the cartridge undergoes a rather violent shock which may cause the projectile 4 to be driven at least partly out of the front end of the cartridge case. In this case, even if the projectile remains partly held by the cartridge case, the volume in which the propelling powder charge is burning is modified so that firing becomes irregular.

Of course, if the projectile 4 is loosened entirely from the cartridge case, the propelling charge may come into contact with a hot gun barrel and premature firing can then take place with the dangers it involves.

In order to obviate these drawbacks, it has been proposed to brake the movement of the cartridge at the end of its travel in the cartridge chamber, so that it is less violently stopped.

For instance, such a braking was obtained by a deformation of the shoulder e of cartridge case 2, this deformation being produced when said shoulder comes into contact with an abutment carried with the gun barrel.

However such a construction does not always make it possible to position the cartridge accurately in the cartridge chamber, especially when the speed at which the cartridge is introduced into the cartridge chamber is very high, as it is the case for automatic guns having a high rate of firing.

In this case, due to the unavoidable differences existing in the manufacture of the cartridge case and also to the variations in the rate of firing of the gun, the violence of the shock of shoulder e against the abutment carried by the gun barrel varies and the positioning of the rear edge of the cartridge at the end of its introduction in the cartridge case also varies.

The present invention is intended to obviate this drawback.

As illustrated by Fig. 1, the cartridge case 2 includes at least two bearing areas located one ahead of the other so as to cooperate with two abutments provided in the cartridge chamber and also located at a distance from each other in the axial direction.

According to my invention, said abutments and said bearing areas are shaped and positioned in such manner that the cartridge, when it is near the end of its inward movement with respect to cartridge chamber 1, is first braked by deformation of one of said bearing areas against the corresponding cartridge chamber abutment, then positioned in a very accurate manner by engagement of the second bearing area against the corresponding cartridge chamber abutment. The first area will be hereinafter called "braking area" and the second one "positioning area."

It will be understood that owing to such an arrangement and to the fact that the braking area and the positioning area act one after the other, it will be possible to obtain a more accurate positioning of the cartridge at the end of its introduction, without subjecting the cartridge to violent shocks which might loosen the projectile 4 in the neck of the cartridge case.

This will be possible because the braking area and the corresponding abutment of the cartridge chamber can be devised in such manner that when, subsequent to their cooperation, the positioning area comes into contact with its abutment, the speed of the cartridge has been sufficiently lowered to reduce the shock of the positioning area against the rear abutment to an admissible value.

The parts will be arranged in such manner that, account being taken of the functional characteristics of the gun and of the circumstances of firing and of all possible firing circumstances, in the most unfavorable case, that

is to say when the speed of introduction of the cartridge is the lowest possible, the deformation of the braking area just enables the cartridge to fit in the cartridge chamber without any shock of the positioning area against the rear abutment of the cartridge chamber. In all other firing circumstances, the positioning area will have an active function and will come to bear against its abutment with a slight shock involving no risk of loosening projectile 4 from the neck of the cartridge case.

For instance, in the case of a gun of the open breech type, the braking area may achieve by itself a correct positioning of the cartridge when the first round is being fired, that is to say when the breech starting from its rear position, where it is held by the detent system, moves toward the front under the only action of the recuperator spring. In guns of this type, when a burst is being fired, the breech-block has a recoil movement of a high amplitude at the end of which it compresses a damping and accelerating spring the action of which is added to that of the recuperator spring so as to return toward the front the breech case the speed of displacement of which is then higher, at the end of its frontward stroke, than the speed it had when the first round was being fired. Thus when firing a burst, the positioning area will act, after deformation of the braking area, for every shot that is fired.

Preferably, the braking area of the cartridge case is located ahead of the positioning area and for this purpose, the braking area is advantageously constituted by the shoulder *e* of the cartridge case 2. The positioning area is then constituted by an annular flange *b* located in the rear part of the cartridge case (for instance immediately ahead of the extractor groove), said flange having a diameter higher than the diameter of the rear part of the body of the cartridge case.

In order to enable the shoulder *e* of cartridge case 2 to perform, by deformation, the braking effect expected therefrom, the abutment of the cartridge chamber 1 that cooperates with said shoulder *e* preferably has a shape different from that of said shoulder so that the latter comes to fit exactly against said abutment only at the end of its movement but at the beginning of the braking period a gradual deformation of said shoulder is produced which causes the cartridge to be slowed down gradually as it is being forced into the cartridge chamber.

For instance, advantageously, the abutment *e*₁ of the cartridge chamber and the shoulder *e* of the cartridge case are both of frusto-conical shape but their respective apex angles are different from each other, the shoulder *e* of the cartridge case having an apex angle (for instance averaging 45°) greater than the apex angle of the abutment *e*₁ of the cartridge chamber 1 (which for instance averages 30°).

With such a gun, a correct positioning of the cartridge in the cartridge chamber will be ensured:

When the first round is being fired, by the mere deformation of the shoulder *e* of the cartridge case 2 to come against the abutment *e*₁ of the cartridge chamber (flange *b* being then merely brought into contact against its abutment, at the rear of the cartridge chamber).

When the following rounds are fired, during a burst of fire, the positioning of the cartridges is obtained both by deformation of shoulder *e* and by a slight shock of flange *b* against the rear edge of the cartridge chamber.

Figs. 2 and 3 show the most characteristic positions during the deformation of shoulder *e*.

Said shoulder, after it has come into contact with the abutment *e*₁ of the cartridge chamber (Fig. 1) is gradually deformed so as to fit exactly against abutment *e*₁. This deformation, which produces a progressive braking, corresponds to a relative displacement which, for a 20 mm. gun, may average 2 mm. (Fig. 2). Then the cartridge still further moves by a distance *a* (in the above considered example, averaging 1.2 mm.) in the course

of which the braking action still takes place by driving shoulder *e* rearwardly by this distance (1.2 mm.). This complementary stroke then brings the flange *b* of the cartridge base against its abutment *b*₁ (Fig. 3). The cartridge is then ready for firing.

Fig. 4 shows a type of gun for which such an arrangement as above described is particularly advantageous. Such gun includes two locking members 5 which bear directly against the end face of cartridge case 2 by their inner ridges X. The locking members are brought into locking position by pivoting about this diametral line X once the cartridge has been positioned in the cartridge chamber, this displacement being produced by a part 6 capable of having a complementary forward displacement once the locking members have finished their frontward movement.

With a gun of this type, the fact that every cartridge is always positioned in exactly the same position at the end of its introduction movement into the cartridge chamber makes it sure that the pivoting movement of the locking members takes place in the same conditions and that the limitation of the axial movement of the locking members is always produced by the fact that ridge X is in contact with the rear end face of the cartridge case. Therefore, the cartridge cannot be driven too deeply into the cartridge chamber, in which case the locking members would come into contact with the rear edge of the gun barrel, thus deteriorating said gun barrel or said locking members.

In a general manner, while I have, in the above description, disclosed what I deem to be practical and efficient embodiments of my invention, it should be well understood that I do not wish to be limited thereto as there might be changes made in the arrangement, disposition and form of the parts without departing from the principle of the present invention as comprehended within the scope of the accompanying claims.

What I claim is:

1. In combination, a gun having a cartridge chamber provided with a front annular abutment and a rear annular abutment, and a cartridge for use in said gun including a cartridge case having two annular projecting bearing areas for cooperation with said abutments respectively, said areas being shaped and positioned along said cartridge case to cause one of them to be in contact with the corresponding cartridge chamber abutment before the other bearing area comes into contact with the other cartridge chamber abutment, said bearing area which is first in contact with the corresponding cartridge chamber abutment being of a shape different from that of said last mentioned cartridge chamber abutment so as to be deformed when coming into contact therewith, whereby the movement of the cartridge in the cartridge chamber is braked during a short period immediately preceding its final fixation in said chamber.

2. In combination, a gun having a cartridge chamber provided with a front annular abutment and a rear annular abutment, and a cartridge for use in said gun including a cartridge case having a front annular shoulder for cooperation with said cartridge chamber front annular abutment, said shoulder and said front abutment being of different shapes respectively so that said shoulder must undergo deformation to come to fit against said front abutment, said cartridge case further having a rear projecting annular bearing area for cooperation with said cartridge chamber rear annular abutment, the distance between said shoulder and said rear bearing area being greater than the distance between said abutments, whereby the movement of the cartridge in the cartridge chamber is braked during a short period immediately preceding its final fixation in said chamber.

3. In combination, a gun having a cartridge chamber provided with a front frusto-conical abutment and a rear annular abutment, and a cartridge for use in said

gun including a cartridge case having a front frusto-conical shoulder for cooperation with said cartridge chamber front abutment, the apex angles of said shoulder and said front abutment respectively being different so that said shoulder must undergo deformation to come to fit against said front abutment, said cartridge case further having a rear annular flange projecting therefrom for cooperation with said cartridge chamber rear abutment, the distance between said shoulder and said flange being greater than the distance between said cartridge chamber abutments, whereby the movement of the cartridge in the cartridge chamber is braked during a short period immediately preceding its final fixation in said chamber.

4. In combination, a gun having a cartridge chamber provided with a front frusto-conical abutment and a rear annular abutment, and a cartridge for use in said gun including a cartridge case having a front frusto-conical shoulder for cooperation with said cartridge chamber front abutment, the apex angle of said shoulder being greater than the apex angle of said front abutment

so that said shoulder must undergo deformation to come to fit against said front abutment, said cartridge case further having a rear annular flange projecting therefrom for cooperation with said cartridge chamber rear abutment, the distance between said shoulder and said flange being greater than the distance between said cartridge chamber abutments, whereby the movement of the cartridge in the cartridge chamber is braked during a short period immediately preceding its final fixation in said chamber.
